US00D599800S

(12) **United States Design Patent**
Klein et al.

(10) **Patent No.:** US D599,800 S
(45) **Date of Patent:** ** Sep. 8, 2009

(54) **ETHERNET TO USB ADAPTER**

(75) Inventors: **Sandro David Klein**, Cypress, CA (US); **Hungbing Chen**, Tustin, CA (US); **Eran Weinberg**, Los Angeles, CA (US)

(73) Assignee: **Cisco Technology, Inc.**, San Jose, CA (US)

(**) Term: **14 Years**

(21) Appl. No.: **29/330,460**

(22) Filed: **Jan. 7, 2009**

(51) **LOC (9) Cl.** **14-02**

(52) **U.S. Cl.** **D14/433**

(58) **Field of Classification Search** D14/356-358, D14/383-387, 432-439, 474, 480.1-480.7, D14/483, 484.1, 496, 137, 203.1-203.8, 217, D14/238.1, 299; D13/133, 153, 154, 158, D13/162, 173, 184, 199; 439/76.1, 131, 439/447, 449, 452, 455, 502, 607-610

See application file for complete search history.

(57) **CLAIM**

The ornamental design for an ethernet to USB adapter, as shown and described.

DESCRIPTION

FIG. 1 is a top view showing our new ethernet to USB adapter; FIG. 2 is a side view thereof;

FIG. 3 is another side view thereof;

FIG. 4 is a top perspective view thereof;

FIG. 5 is an end view thereof;

FIG. 6 is another end view thereof; and,

FIG. 7 is a bottom view thereof.

The broken lines in the drawings depict unclaimed portions of the ethernet to USB adapter and form no part of the claimed design.
